PIVOTAL AUXILIARY SEAT OR SIMILAR ARTICLE

Rodney G. Sparrow, 37 Pierce Road, Watertown, Mass.
02172, and Richard S. Sparrow, 8 Wingate Road, Lexington, Mass. 02173

Filed Oct. 9, 1973, Ser. No. 404,161

Term of patent 14 years

Int. Cl. D6—01

U.S. Cl. D6—49

FIG. 1

FIG. 2

FIG. 3

FIG. 4

FIG. 5

FIG. 1 is a perspective view of a pivotal auxiliary seat construction shown in operative relationship to a desk fragment indicated in broken lines.

FIG. 2 is a plan view;

FIG. 3 is another perspective view of an opposite side of the pivotal auxiliary seat from that shown in FIG. 1;

FIG. 4 is a front elevational view; and

FIG. 5 is a side elevational view.

We claim:

The ornamental design for a pivotal auxiliary seat or similar article, substantially as shown.
